United States Patent Office

Des. 209,399
Patented Nov. 28, 1967

209,399

FILTER ATTACHMENT FOR SPARK PLUGS

Myron J. Weiner, Los Angeles, Calif., assignor to Hallett Manufacturing Company, Los Angeles, Calif., a corporation of California

Filed Dec. 6, 1966, Ser. No. 4,943

Term of patent 14 years

(Cl. D26—1)

FIG. 1.

FIG. 2.

FIG. 3.

FIG. 4.

FIG. 1 is a side elevation of a filter attachment for spark plugs, showing my new design;

FIG. 2 is an elevation of the other side thereof;

FIG. 3 is a top plan thereof; and

FIG. 4 is a bottom plan thereof.

I claim:

The ornamental design for a filter attachment for spark plugs, as shown.
